UNITED STATES PATENT OFFICE.

ERNEST N. DORING, OF NEW YORK, N. Y.

COMBINED DESK AND FOLDING WARDROBE-BED.

SPECIFICATION forming part of Letters Patent No. 244,566, dated July 19, 1881.

Application filed September 7, 1880. (No model.)

To all whom it may concern:

Be it known that I, ERNEST N. DORING, of the city, county, and State of New York, have invented a new and useful Improvement in 5 Combined Desk and Folding Wardrobe-Bed, of which the following is a specification.

Figure 1 is a front elevation of the improvement. Fig. 2 is a side elevation, partly in section.

10 The object of this invention is to furnish folding wardrobe-beds provided with desks so constructed that they can be opened and used with as much facility as though they were only desks, and which at the same time 15 will not interfere with the opening and closing of the wardrobe-beds.

A represents the rear or stationary part of a wardrobe-bed, and B represents the forward folding part.

20 To the forward edges of the sides of the folding part B are attached, at a suitable height from the floor, brackets C. To the inner sides of the brackets C are attached the ends of a board, D, which forms the inner and 25 stationary part of the desk-top, and which may be horizontal or slightly inclined.

To the outer edge of the board D is hinged the edge of the board E, which forms the movable part of the desk-top. The board E is hinged 30 in such a manner that when turned down its edge may rest against the edge of the board

D. and leave the upper surface of the two boards smooth and in the same plane. The board E is made of such a width that when turned up or closed its upper edge may rest 35 against the front of the forward part, B, of the wardrobe-bed.

If desired, the hinged part E of the desk-top may be provided with hinged or jointed arms to support it when turned down, which 40 arms are not shown in the drawings.

If desired, a curved board may be attached to the outer side of the board E, as shown in Fig. 2, for ornamental purposes, in which case 45 the space between the said curved board and the board E may be used for holding papers, access to the said space being had through a door in the said board E.

Having thus described my invention, I claim as new and desire to secure by Letters 50 Patent—

A wardrobe-bed consisting, essentially, of the stationary back A, the folding front B, the brackets C, the inner board, D, forming the stationary part of desk, and the outer 55 board, E, forming the hinged movable part of desk, as shown and described.

ERNEST N. DORING.
